RECESSED AUTOMATIC BOTTOM CARTON

Hubert V. Bolding, Clarksville, Ind., assignor to Standard Packaging Corporation, New York, N.Y., a corporation of Virginia

Original application Mar. 23, 1955, Ser. No. 496,111. Divided and this application Feb. 26, 1958, Ser. No. 717,787

3 Claims. (Cl. 229—39)

My invention relates to a single blank collapsible carton having a recessed automatic bottom. This carton may be completely manufactured by automatic machinery, shipped to the user in collapsed condition, loaded into a packing machine and automatically erected to article-receiving position.

This application is a division of my application Serial No. 496,111, filed March 23, 1955, and entitled "Recessed Automatic Bottom Carton," now Patent No. 2,866,588, granted December 30, 1958.

While automatic bottoms have been employed in cartons for a number of years, the instant invention provides an automatically erectable carton which includes a recessed automatic bottom suitable for the resilient support of fragile articles, such as sealed beam headlights and the like, which may be placed in the carton with their most fragile portion resting on the bottom and through the recessed construction be protected from damage due to shock and rough handling.

Further, it is possible with this carton to provide a chest-like carton with a leg structure which may be utilized for packaging candy and the like without any possibility of creating misconception as to the amount of candy held within since the leg structure and raised bottom are immediately apparent.

Other objects and meritorious features of the invention will be apparent from the following description taken in conjunction with the drawings wherein like numerals refer to like parts throughout the figures and wherein:

Fig. 1 is a perspective view of a chest-type carton in erected condition which embodies the invention;

Fig. 2 is a perspective view of the chest-type carton of Fig. 1 in collapsed condition;

Fig. 3 is a plan view of the single blank from which the carton of Figs. 1 and 2 is made;

Fig. 4 is a perspective bottom view of the carton of Fig. 1; and

Fig. 5 is a plan view of a portion of a single blank of modified design.

Referring now to Figs. 1-4, it will be seen that the chest carton is made from the single blank of Fig. 3 which is cut and scored to form four outer walls 15, 16, 17 and 18, and an upper end attaching member 19 and a lower end attaching member 14. Glue areas are indicated on the blank.

To provide a carton having the same surface of the blank showing at the inner walls and the outer walls, inner wall panels 20, 21, 22 and 23 extend downwardly from the outer walls 15-18 and are glued in face-to-face engagement therewith.

The recessed bottom is formed in part by means of four bottom recessing panels 24, 25, 26 and 27 which extend upwardly from the bottom edges of the outer walls 15-18 and are glued in face-to-face engagement therewith. Four bottom members 28, 29, 30 and 31 are hinged to the upper edges of the recessing panels 24-27 and these bottom members 28-31 in cooperation with the two diagonally opposed bottom folding motion trans-

2

mitting tabs 32 and 33 form an automatically erectable and collapsible recessed bottom.

The bottom folding tab 32 is integrally hinged to the hinge edge 34 of the bottom member 28, this hinge edge 34 defining 45-degree angles, when the carton is in erected condition, with the upper edges 35 and 36 of the bottom recessing members 24 and 25 as best seen in Fig. 4. Likewise, the bottom folding tab 33 is integrally hinged to the hinge edge 37 of the bottom member 30, this hinge edge 37 defining 45-degree angles, when the carton is erected, with the upper edges 38 and 39 of the bottom recessing members 26 and 27.

It will be noted that the bottom members 28 and 30 are triangular in configuration and that glue areas 40 and 41 on the blank are shown on the rectangular bottom members 29 and 31 for the bottom folding tabs 32 and 33, respectively.

The edge 42 of the inner wall panel 20 is cut to enable adherence of the upper attaching member 19 to the inner face of the outer wall 15 above the bottom members 28-31. The lower attaching member is affixed to the bottom recessing member 24 below the bottom members 28-31.

The recessed bottom of the instant invention enables the provision of a partially open supporting framework beneath the bottom members 28-31 by forming openings by mating cutouts in the lower portions of the outer walls 15-18 and the adjacent portions of recessing members 24-27. In the embodiment shown in Figs. 1-4, elongated openings 43, 44, 45 and 46 are formed on either side of and including a portion of the score lines between the outer walls 15-18 and the recessing members 24-27, these openings 43-46 being positioned intermediate the side edges of the outer walls 15-18 and recessing members 24-27. This construction results in the formation of double thickness corner legs 47, 48, 49 and 50 (Fig. 4), each of which comprises two sections at right angles to each other with the outer wall thickness of the legs being uncut to present a tailored appearance as well as a rigid construction.

In Fig. 5 is shown a modification wherein an upper surface member 51 extends from the inner wall 23, this surface member 51, upon erection of the carton, providing a top cover over the elements of the automatic bottom which has a visible surface of the same material as the outer wall surface of the carton. This modification improves the tailored appearance of the carton without requiring the use of separate parts or a blank stock having expensive surface material on both sides.

The collapsed carton of Fig. 2 may be erected by automatic carton loading machinery which applies pressure on the side edges of the flattened carton in the direction of the arrows as shown. Various portions of the blank are cut-away to facilitate assembly and reduce erection stresses. Stapling, stitching, and the like, as well as gluing may be employed to fixedly secure the panels in proper relation.

Various modifications within the spirit of this invention will be apparent to those skilled in the art and for that reason I wish to limit myself only within the scope of the appended claims.

I claim:

1. A single-blank collapsible carton comprising four outer walls permanently hinged together to provide a continuous and collapsible outer wall structure, all of said hinge lines between adjacent walls being parallel, two of the walls lying in one plane and the other two lying in another plane in the collapsed condition of the carton, four bottom recessing panels, each hingedly connected to the bottom edge of one of said outer walls and extending upwardly from the bottom edge in fixed face-to-face relation to the inner face of the

corresponding outer wall to provide a double thickness leg at the base of each of the said four outer walls, and four bottom flaps each hingedly connected to the upper edge of a bottom recessing panel, each of an opposed pair of said bottom flaps having a diagonal fold line which divides the flap into a part which is hinged to the respective bottom recessing panel and a motion-transmitting tab affixed in face-to-face relation with an adjacent bottom flap, the diagonal fold lines of each of the opposed pair of said bottom flaps being at an angle of 45 degrees to the hinge connecting the bottom flap and the corresponding bottom recessing panel, said motion-transmitting tab permitting the motion-transmitting flap to be folded against the flap to which it is hinged in the collapsed condition of the carton serving to erect the two adjacent bottom flaps when the corresponding outer walls are pivotally separated from collapsed condition.

2. A single blank, self-erectable carton comprising four rectangular outer walls permanently hingedly connected to provide a continuous, collapsible outer wall structure, two of the walls lying in one plane and the other two lying in another plane in the collapsed condition of the carton and adjacent walls being at right angles to each other in the erected condition of the carton, four folded-back bottom recessing panels of equal height, each hingedly connected to the lower edge of one of the outer walls and extending upwardly from the bottom edge in fixed face-to-face relation to the inner face of the corresponding outer wall to provide a double thickness wall between the hinge line and the recessed bottom, at least one of said double thickness walls being cut away to

remove coterminous portions of the outer wall and the recessing panel hinged thereto to define spaced-apart supporting legs at the corners, and four bottom flaps each hingedly connected to the upper edge of a folded-back recessing panel, each of an opposed pair of said bottom flaps having a diagonal fold line which divides the flap into a part which is hinged to the respective bottom recessing panel and a motion-transmitting tab affixed in face-to-face relation with an adjacent bottom flap, the diagonal fold lines of each of the opposed pair of said bottom flaps being at an angle of 45 degrees to the hinge connecting the bottom flap and the corresponding bottom recessing panel, said motion-transmitting tab permitting the motion-transmitting flap to be folded against the flap to which it is hinged in the collapsed condition of the carton serving to erect the two adjacent bottom flaps when the corresponding outer walls are pivotally separated from collapsed condition.

3. A single blank, self-erecting carton as set forth in claim 2 wherein at least one pair of opposed bottom flaps are of predetermined size to provide a surface coextensive with the area defined within the four outer walls.
